UNITED STATES PATENT OFFICE.

ADOLF BUCHWALDER, OF PHILADELPHIA, PENNSYLVANIA, ASSIGNOR, BY DIRECT AND MESNE ASSIGNMENTS, TO JOHN BISHOP HALL, OF SAME PLACE.

MATTING.

SPECIFICATION forming part of Letters Patent No. 617,076, dated January 3, 1899.

Application filed October 17, 1898. Serial No. 693,693. (No model.)

To all whom it may concern:

Be it known that I, ADOLF BUCHWALDER, of Philadelphia, county of Philadelphia, and State of Pennsylvania, have invented certain new and useful Improvements in Matting, of which the following is a full, clear, and exact description.

This invention relates to matting for floors and other purposes of that class composed of strips or links of leather or other material strung upon wires or rods and fastened so as to make a permanent yet flexible structure.

The novelty in the present instance resides in the peculiar construction of the links, whereby they may be quickly and easily placed upon the rods and permitting of the removal of any one of the links and its replacement by a new one or another should occasion require without the loosening or removal of the rod. A mat thus constructed is as efficient as the old forms, as the slots are so inclined in opposite directions as to render it almost impossible for the links to become accidentally disengaged from the rods.

The invention is clearly illustrated in the accompanying drawings, which, with the letters and figures of reference marked thereon, form a part of this specification, and in which—

Figure 1 represents a perspective view of a small portion of a matting embodying my invention. Fig. 2 represents a similar view of one of the strips detached.

Referring to said drawings, A designates the matting, shown as composed of contiguous rows 1, 2, 3, and 4, each row being made up of a plurality of narrow strips B, preferably made of leather or analogous material, which may be fashioned after any desired or ornamental pattern. The strips B are perforated at or near their ends, as shown at x, Fig. 2, and are so arranged when grouped together that the perforated ends of the strips B in one row will lie contiguous to and between the perforated ends of the strips of the next succeeding row, the whole being secured against displacement by rods C, which pass through said perforations, as shown. By this construction it will be seen that each row is

made up alternately of a plurality of strips 50 B and open spaces B', the group of strips in one row lying in the same horizontal plane as and adjacent the spaces B' in the next succeeding row.

The rods are preferably formed of wire, bent 55 at their intermediate portions D in order to provide parallel extensions C', which latter through the perforations x at one edge of the matting, as shown, while the extremities of said extensions are bent, interlocked, or otherwise fastened at the opposite edge of the matting, as will be obvious. Thus the strips B are firmly held in their proper relative position, while at the same time they are free to rotate upon said rods when the matting is 60 rolled or folded for transportation or other purposes.

In order to facilitate in assembling the strips B and applying thereto the fastening-rods C', I provide said strips with open slots 70 x', (shown in Fig. 2,) which extend from one edge thereof into each of the perforations x. Thus the strips may be quickly and easily placed upon the rods C, as the pliable or yielding nature of the leather will permit said slots 75 to expand to admit the rods, as will be apparent. As will be seen from Fig. 2, these slots incline in opposite directions toward each other at the outer ends, so that when the links are in position upon the rods they will 80 be securely held against displacement therefrom.

It is apparent, of course, that the shape or pattern of the strips B may be changed at will, and it is also obvious that instead of 85 forming each row of a plurality of strips, as shown, I may substitute therefor solid blocks composed of leather or paper-pulp or the like and afterward subjecting the same to a process of hardening.

It is also obvious that many and varied patterns may be formed in the construction of the matting, and I do not wish to be understood as limiting myself to the exact pattern herein shown and described, but reserve the 95 right to alter the same in such manner as may be held to fairly fall within the spirit and scope of my invention.

Having thus described my invention, what I claim, and desire to secure by Letters Patent, is as follows:

5 A matting, comprising a plurality of juxtaposed strips, said strips being provided with perforations and open slots leading in oppositely-inclined directions from one edge of

each strip to each of said perforations, and rods adapted to said perforations, whereby said strips are held in assembled position.

ADOLF BUCHWALDER.
